UNITED STATES PATENT OFFICE.

WILLIAM S. McLEWEE, OF YARDLEY, PENNSYLVANIA.

ELECTRIC SWITCH.

964,536.

Specification of Letters Patent. Patented July 19, 1910.

Application filed February 13, 1909. Serial No. 477,497.

To all whom it may concern:

Be it known that I, WILLIAM S. McLEWEE, a citizen of the United States, residing at Yardley, in the county of Bucks and State 5 of Pennsylvania, have invented certain new and useful Improvements in Electric Switches, of which the following is a specification.

My invention relates to improvements in 10 electric switches and my invention comprises in its construction a base, a switch and a socket adapted to receive a plug-cut-out.

The object of my invention is to provide 15 a switch slidably mounted upon a base. Said base having housings thereon to inclose the gap formed when the switch is open and the circuit broken, so as to prevent the accidental injury to a person handling the switch.

20 A further object of my invention is to so construct the connections between the switch and the plug-cut-out sockets that perfect insulation of the parts is provided; and a still further object of my invention is 25 to provide novel means for operating the switch.

Referring to the accompanying drawings: Figure 1. is a plan view of my improved switch; Fig. 2. is a vertical section on line 30 2-2 Fig. 1; Fig. 3. is a vertical section on line 3-3 Fig. 1; Fig. 4. is a vertical section on line 4-4 Fig. 1; Fig. 5. is a vertical section on line 5-5 Fig. 1; and, Fig. 6. is a perspective view of the contact-post and the 35 contact-plate detached.

In the drawings in which like references 40 refer to like parts, 1 represents the base made of porcelain or other suitable insulating material. Upon the base are formed the housings for the switch-rods and projecting walls to form sockets for the plug-cut-outs and said base is also provided with recesses and depressions for the reception of the several parts. The base 1 is provided 45 upon the upper side with an enlargement which forms the housing 2 for the switch rods 3 and 4, which latter slide longitudinally in apertures formed in said housing 2.

The switch-rods 3 and 4 are connected 50 at one end by a cross-bar 5, of insulating material. A plate 8, secured to said cross-bar 5, is provided upon its outer end with a handle 9 by which the switch-rods may be moved longitudinally through the apertures 55 formed in the housing 2. A second handle is also provided, for operating the switch-

rods, consisting of an arm 12 pivotally mounted in a bearing 13 secured in the base 1. Said arm 12 is connected by the bolt 14 with the plate 8 secured to the cross-bar 5 and upon the arm 12 is a handle 15 with which the arm 12 can be conveniently moved to operate the switch-rods. By providing two handles the switch may be conveniently operated when placed in a vertical or horizontal position and when located in a high or low position upon the switch board.

The contact-posts 17 and 18, shown in detail in Fig. 6, are secured upon the base 1 at either end of the housing 2 and in alignment with the apertures formed in said housing for the switch-rods. Said contact-posts 17 and 18 are made of a spring-plate folded upon itself so that the free ends thereof, having the curved portions 20 will impinge against the switch-rod when it is forced between them and make a perfect contact. The contact-posts 17 and 18 are held in depressions formed in the base, by the contact plates 22 and 23 having bifurcated ends which are adapted to pass over the base 24 of the contact-posts 17 and 18 and at either side of the vertical portion 25 of said contact-posts. Said contact-posts are secured by screws 26 and 27 passing 35 through the base.

The contact-plates 23 have binding-screws 29 thereon to which are connected the line wires 30 and 31. The switch-rods 3 and 4 are constantly in contact with the 90 contact-posts 18. When said switch-rods are moved into the position shown in full lines in the drawings the contact is made with the contact-posts 17 and the circuit is completed. When the switch-rods are withdrawn into the position shown in dotted lines Fig. 2, the circuit will be broken and the gap formed between the ends of the switch-rods and the contact-post 17 will be 95 covered by the housing 2 encasing the 100 switch-rods.

The contact-plate 22 connects the contact-post 17 with the metal sleeve 32, in the plug-cut-out socket 6. The contact-plate 22 is provided with an aperture which permits 105 said contact-plate to encircle the bosses 35, formed upon the base 1. Said contact-plate 22 is secured upon the base by a screw 26 which holds said contact-plate securely 110 in contact with the contact-post 17 and the sleeve 32.

The metal sleeve 32 is made with a bot-

tom 33 having a flange 34 formed thereon, which flange fits into the aperture formed in the contact-plate 22 and the edge of the flange 34 is pressed around the contact-plate 5 to securely fasten the sleeve and the contact-plate together. The aperture thus formed in the bottom 33 of the sleeve will permit the sleeve and the contact-plate to encircle said boss 35 and the said parts will be securely held in the bottom of the socket by the screw 26 passing through the base. The contact-screw 40, passing through said boss 35 forms the other point of contact for the plug-cut-out. The said screws 40 are connected with the line wires 41 and 42 by the plates 43. By extending the boss 35, a sufficient height above the contact-plate 22 and the bottom of the sleeve 32, as shown in the drawings, the head of the contact-screw 40 10 will be sufficiently separated from the contact-plate 22 and the metal sleeves 32, to form a complete insulation between said parts and thus avoid the necessity of providing insulating washers in the plug-cut-out 15 sockets, and also to reduce the number of parts, simplify the construction and reduce the cost of the same.

Having thus described my invention I claim and desire to secure by Letters Patent:

30 1. In an electric switch having a sliding-rod and contact-posts, the combination of a base having a housing formed thereon, said housing being made of insulating material and having an aperture formed therein to receive said rod, said housing located be-

tween said contact-posts and adapted to fill the gap between one of said contact-posts and said rod when the latter is withdrawn from the last mentioned contact-post to break the circuit.

40

2. In an electric switch, the combination of sliding-rods, a base having a housing formed thereon formed of insulating material, a cross-piece of insulating material connecting said rods, a handle extending in a line parallel with said rods, a handle pivoted in said base and pivotally connected with said first mentioned handle and extending at right angles to the latter handle and contact-posts located at the ends of said housing adapted to embrace said rods.

45

3. In an electric switch having sliding switch rods and a base, the combination of contact-posts consisting of a plate folded upon itself with curved portions formed therein to embrace said rod, said contact-post having outwardly projecting portions forming a base, a contact plate adapted to engage the said outwardly projecting portions of said contact-post, said contact-plate 50 having a recess formed therein to embrace the central portion of said contact-post and means for securing said contact-plate to the base of the switch.

55

In testimony whereof I affix my signature 60 in presence of two witnesses.

WILLIAM S. MCLEWEE.
